DESIGN FOR A COMBINED WALL BRACKET AND MIRROR

Helge G. Blomgren, Rockford, Ill.

Application June 5, 1940, Serial No. 92,834

Term of patent 3½ years

To all whom it may concern:

Be it known that I, Helge G. Blomgren, a citizen of the United States, residing at Rockford, in the county of Winnebago and State of Illinois, have invented a new, original, and ornamental Design for a Combined Wall Bracket and Mirror, of which the following is a specification, reference being had to the accompanying drawing, forming part thereof.

In the drawing:

Figure 1 is a front elevational view of a combined wall bracket and mirror, embodying my design;

Fig. 2 is a side elevational view, and

Fig. 3 is a plan view.

I claim:

The ornamental design for a combined wall bracket and mirror, substantially as shown.

HELGE G. BLOMGREN.
